APPARATUS FOR MIXING OR AGITATING
COATING AND GRANULAR MATERIALSLoren Hale, Tulsa, Okla., assignor to Stuk-O-Rite,
Inc., Tulsa, Okla., a corporation of Delaware

Application January 24, 1949, Serial No. 72,498

4 Claims. (Cl. 259—151)

1

The present invention relates to apparatus for mixing coating materials, such as stucco, plaster, paint, etc., or for agitating granular material in dry state, such as sand used to sand-blast surfaces for cleaning and other purposes.

The principal object of the invention is to provide apparatus of this character which is simple in construction, inexpensive to manufacture and maintain in good repair, efficient in operation and easily cleaned considering the character of the material acted upon during its operation.

The apparatus is particularly well adapted, although not limited to use with spray guns of the character disclosed in my copending application for patent filed January 24, 1949, Serial No. 72,497, issued as Patent No. 2,571,874.

Another object is to provide apparatus for mixing heavy materials such as stucco, and materials using hair or fibre as a binder, such as plaster and roof coating, which is not likely to become clogged at the outlet orifice for the mixed material.

Other objects and advantages will appear in the following detailed description of the preferred embodiment of my invention, taken in connection with the accompanying drawings, forming a part of this specification, and in which drawings:

Fig. 1 is a perspective view looking mainly toward a side of the apparatus provided with covered hand holes, the apparatus being shown closed and sealed for the purpose of subjecting the charge of material acted upon to superatmospheric pressure.

Fig. 2 is a similar view but looking more toward a lower cleaning outlet of the apparatus and a valve controlled exit for the material acted upon.

Fig. 3 is a view partly in elevation and partly in vertical central section through the apparatus.

Figs. 4 and 5 are horizontal sectional views on substantially the lines 4—4 of Fig. 1 and 5—5 of Fig. 2, respectively, Fig. 5 being on a slightly enlarged scale.

Fig. 6 is a detail view partly in elevation and partly in vertical section at the upper end of an agitator shaft and associated bearing and support elements.

Figure 7 is an enlarged sectional view on the line 6—6 of Figure 5.

The apparatus comprises a tank 8 for holding the material acted upon, including an upright cylindrical body portion 9, a preferably dished bottom 10 and a top 11 which may be provided with an upstanding flange 12 surrounding a charging opening 13; a cap 14 for the charging

opening; suitable means 15 for detachably sealing the cap 14 in fluid tight closing relation to the charging opening; means 16 for introducing air under superatmospheric pressure into the upper portion of the tank; an upright drive shaft 17 coaxial with the cylindrical body portion 9 of the tank, extending through the bottom 10 and preferably to a point adjacent the top 11; motion transmitting means 18 operatively connected to the shaft 17 for imparting rotation to the latter in a predetermined direction, as indicated by arrows in Figs. 3, 4 and 5, from any suitable prime mover, not shown in the drawings; one or more agitator blades 19 adjacent the upper portion of the tank and connected to the shaft 17, preferably by a hub 20 provided with set screws 21, the blade or blades extending laterally of the shaft; one or more agitator blades 22 closely adjacent the tank bottom 10 and connected to shaft 17 preferably by a hub 23 provided with set screws 24, the blade or blades 22 extending laterally of the shaft in close proximity to the inner face 25 of the cylindrical portion 9 of the tank and in close proximity to the upwardly facing surface 26 of the bottom 10, as shown in Fig. 3; a conduit section 27 for outlet of the material acted upon by the blades 19 and 22 and air under superatmospheric pressure in the tank, the conduit section leading from the cylindrical body portion 9 of the tank in a substantially tangential direction thereto, and counter to the direction of rotation of shaft as shown in Fig. 4, the inlet 28 of the way 29 of the conduit section 27 being in a zone slightly above the zone of rotation of the blade or blades 22, as shown in Fig. 3; and a clean-out pipe 30, provided with a closure 31, at the lower portion of the tank.

The cap 14 may be provided with suitable accessories, such as a pressure gauge 32, a safety valve 33 and a manually operable relief valve 34, and a suitable valve 35, such as a gate valve may be provided in connection with the conduit section 27. I have also shown handholes 36 in the cylindrical body portion 9 for access to the hub 23 and the set screws 24, as well as to facilitate cleaning of the tank and internal parts, these handholes being normally closed by doors 37 secured in place by spiders 38 and bolts 39 in the usual or any approved manner. The tank 8 is shown supported on any suitable surface by legs 40 and the upper end of shaft 17 is shown supported by a diametrical brace 41 secured to the body portion of the tank, and supporting any suitable antifriction bearing 42 provided with a cap 43 to exclude material in the tank from con-

tact with the bearing surfaces. If desired a collar 44 provided with a set screw 45 may be provided on shaft 17 beneath hub 20 to assist in holding the hub 20 in the desired position along shaft 17 and to aid in adjusting the blade or blades 19 and hub 20 so that the former will rotate in the desired zone in the tank, as motion is imparted to shaft 17.

The blade or blades 19 are each preferably inclined upwardly and forwardly as shown in Fig. 3 so as to exert a downward thrust upon the material in the tank when rotated and the blade or blades 22 are preferably inclined upwardly and rearwardly as shown in Figs. 3, 4, 5 and 7, so as to exert an upward thrust upon the material in the tank when the shaft 17 is rotated in the direction indicated by the arrows.

When the tank bottom 10 is of dished formation, the blade or blades 22 are cut so that their lower margins 46 conform to the radial section of the bottom 10 as shown in Fig. 3. If desired, blade 22 may be provided with a reinforcing web 47 cast integral therewith or welded in place, the web being normal to the plane of the blade as shown in Fig. 7.

The clean-out pipe 30 is preferably a continuation of a trough 48 of concavo-convex cross section formed integral with the dished tank bottom 10 and located so as to provide a trough-like depression 49 leading from adjacent the axial center of the tank to the pipe 30 as shown more particularly in Figs. 3, 4 and 5.

The means 15 may comprise a plurality of C-clamps each embodying a C-body 51 pivoted at one end as by pin 52 to lugs 53 extending from the top 11 and flange 12, and a thumb or pressure screw 54 at the other end of the body 51 adapted to bear upon the cap 14.

In practice, the tank 8 may be charged with the material to be mixed or agitated, through opening 13, valve 35 first being closed. Upon imparting rotation to the shaft 17, the blades 19 and 22 will exert downward and upward thrusts, respectively, upon the material, and the attendant may observe the mixing of the material through the opening 13. When the material is mixed to the extent desired, the cap 14 is placed in sealed relation to the flange 12, closing the opening 13, whereupon air under superatmospheric pressure is introduced into the tank by means 16. The valve 35 may then be opened to permit the material to find exit through the conduit section 27. Motion is imparted to shaft 17 while the material is finding exit from the tank, and, because of the location of the zone in which the blade or blades 22 operate, with respect to the inlet 28 to the way 29 of conduit section 27 a turbulence of the material occurs in the zone of operation of the blade or blades 22 and in the zone of the conduit inlet 28 to prevent clogging of the inlet. I have found this to be important especially when the material acted upon is heavy, such as stucco or that using hair or fibre as a binder, such as plaster and roof coating.

I have also found that the provision of the trough-like depression 49 in the dished bottom 10 cooperating with the blade or blades 22, shaped and operating in close proximity to the upwardly facing surface 26 of bottom 10, as described, will reduce sedimentation in the trough-like depression, perhaps due to a slight suction created in the depression as the blade sweeps over it. In this way material is not packed tight in the clean-out pipe 30 and an attendant experiences no great difficulty after removing closure 31, in

cleaning the interior of the tank when shutting down for the day or making ready for use of the apparatus in mixing a different batch of material. I have also found that in a similar manner the way 29 of conduit section 27, between the inlet 28 and valve 35, when the latter is closed and mixing is taking place within the tank, will not become packed with material, possibly due to a slight suction created in the way by the blade or blades 22 sweeping in close proximity to the inlet 28 and the fact that the conduit section 27 extends in a direction counter to the direction of rotation of the shaft 17 and hence the direction of travel of the blade or blades 22.

I claim:

1. Mixing apparatus of the character described comprising a tank for holding the material acted upon, including an upright cylindrical body portion, a bottom, and an open top; a cap for said open top; means for detachably sealing said cap to the tank top; means for introducing air under superatmospheric pressure into the upper portion of the tank; an upright drive shaft in said tank coaxial with the cylindrical body portion thereof and rotatable in a predetermined direction; a blade secured to said shaft adjacent the upper portion of the tank and extending laterally thereof, said blade being so inclined to the plane of rotation as to exert a downward thrust upon the material acted upon; a second blade secured to said shaft, movable therewith in close proximity to the bottom of the tank and extending laterally of the shaft in close proximity to the inner face of the cylindrical portion of the tank, said second blade being so inclined to the plane of rotation as to exert an upward thrust upon the material acted upon; and a conduit section for outlet of the material acted upon by the air under superatmospheric pressure in the tank and by said blades, said conduit section opening into said tank at said cylindrical portion at a location slightly above the lowermost end of said cylindrical portion in a substantially tangential direction thereto and counter to the direction of rotation of said shaft, the inlet of the way of said conduit being in a zone slightly above the zone of rotation of said second blade whereby a turbulence of the material acted upon occurs in the zone of operation of said second blade and in the zone of said conduit inlet to prevent clogging of the inlet.

2. In mixing apparatus of the character described, the combination of a tank for holding the material acted upon, said tank comprising an upright cylindrical body portion and a bottom; an upright drive shaft in said tank coaxial with the cylindrical body portion thereof and rotatable in a predetermined direction; a blade secured to said shaft, movable therewith in close proximity to the bottom of the tank, and extending laterally of the shaft in close proximity to the inner face of the cylindrical body portion of the tank; and a conduit section for outlet of the material acted upon, leading from the cylindrical portion of the tank in a substantially tangential direction thereto and counter to the direction of rotation of said shaft, the inlet of the way of said conduit being in a zone slightly above said bottom and the zone of rotation of said blade whereby a turbulence of the material acted upon occurs in the zone of operation of said blade and in the zone of said conduit inlet, to prevent clogging of the inlet.

3. In mixing apparatus of the character de-

scribed, the combination of a tank for holding the material acted upon, said tank comprising an upright cylindrical body portion and a dished bottom; an upright drive shaft in said tank coaxial with the cylindrical body portion thereof and rotatable in a predetermined direction; a blade secured to said shaft, movable therewith in close proximity to the upwardly facing surface of the dished bottom of the tank, and extending laterally of the shaft in close proximity to the inner face of the cylindrical body portion of the tank; and a conduit section for outlet of the material acted upon, leading from the cylindrical portion of the tank in a substantially tangential direction thereto and counter to the direction of rotation of said shaft, the inlet of the way of said conduit being in a zone slightly above said dished bottom and the zone of rotation of said blade whereby a turbulence of the material acted upon occurs in the zone of operation of said blade and in the zone of said conduit inlet, to prevent clogging of the inlet.

4. In mixing apparatus of the character described, the combination of a tank for holding the material acted upon, said tank comprising an upright cylindrical body portion and a dished bottom; an upright drive shaft in said tank coaxial with the cylindrical body portion thereof and rotatable in a predetermined direction; a blade secured to said shaft, movable therewith in close proximity to the upwardly facing sur-

face of the dished bottom of the tank, and extending laterally of the shaft in close proximity to the inner face of the cylindrical body portion of the tank, said blade being so inclined to the plane of rotation as to exert an upward thrust upon the material acted upon; and a conduit section for outlet of the material acted upon, leading from the cylindrical portion of the tank in a substantially tangential direction thereto and counter to the direction of rotation of said shaft, the inlet of the way of said conduit being in a zone slightly above the zone of rotation of said blade and closely adjacent the juncture of the cylindrical body portion and dished bottom whereby a turbulence of the material acted upon occurs in the zone of operation of said blade and in the zone of said conduit inlet, to prevent clogging of the inlet.
